UNITED STATES PATENT OFFICE.

BENJAMIN N. BROUNER, OF HYATTSVILLE, MARYLAND.

COMBINED TOOL BOX AND TRESTLE.

1,404,266.

Specification of Letters Patent. Patented Jan. 24, 1922.

Application filed January 21, 1921. Serial No. 438,980.

To all whom it may concern:

Be it known that I, BENJAMIN N. BROUNER, a citizen of the United States, residing at Hyattsville, in the county of Prince 5 Georges and State of Maryland, have invented certain new and useful Improvements in Combined Tool Boxes and Trestles, of which the following is a specification.

This invention relates to certain new and 10 useful improvements in combined work-benches and supports therefor and it has for its objects among others to provide a simple, light and efficient, yet strong and durable tool-box for use by carpenters and 15 other mechanics, the same combining in the one device a tool-box and a trestle.

The device as a whole can be carried about from place to place, the legs forming the trestle support being foldable against the 20 sides of the tool-box, with means for holding them in either folded or distended position, the tool-box having movably mounted end closures which, when open, serve as supports extended beyond the ends of the tool-box proper, while the center brace or partition in the tool-box serves to greatly strengthen the latter and also serves as means, cooperating with devices carried by the movable ends, for holding such movable 25 ends in open or closed position.

Other objects and advantages of the invention will hereinafter appear and the novel features thereof will be particularly pointed out in the appended claims.

35 The invention is clearly illustrated in the accompanying drawings, which, with the numerals of reference marked thereon, form a part of this specification, and in which--

Figure 1 is a perspective view of my improved combined tool-box and trestle, with the end closures in open position in dotted lines, and one of the sides of the box open.

Figure 2 is a side elevation of the box with the legs folded.

40 Figure 3 is a substantially central vertical longitudinal section through the box, with the legs folded.

Figure 4 is a vertical transverse section on the line 4-4 of Figure 3, looking in the 45 direction of the arrows.

Figure 5 is an enlarged sectional detail, as on the line 5-5 of Figure 1, with parts in elevation, showing one of the end closures in its extended position and the piece of 50 lumber thereon.

Figure 6 is a sectional detail, as on the

line 6-6 of Figure 5, looking in the direction of the arrows.

Figure 7 is a detail in elevation of one of the plates at the corner of the box. 60

Figure 8 is a section, as on the line 8-8 of Figure 7.

Like numerals of reference indicate like parts throughout the several views.

Referring to the drawings, 65

1 designates the top member, 2 and 3 the side portions at the end of the box, and 4 the side portions at the lower portion of the box, and 5 the bottom proper of the box. These are secured together by any suitable 70 means, such as screws or nails, and upon each side above the portions 4 is a door or closure 6 hinged to the portions 4, as shown at 7, and permitting ready access to the interior of the box. Any suitable lock may 75 be provided for locking these doors or closures 6 in closed position, of which 8 in Figure 2 designates the key-hole.

Suitable interior braces or strengthening strips 9 may be employed if desired, and, as 80 seen in Figure 1, these form the rabbets for cooperation with the doors. 10 is a longitudinal substantially centrally disposed partition secured to the top 1 and to the end portions 11 below the points where the doors 85 6 are hinged, as seen in Figure 3. This partition serves to greatly strengthen the box making of the top a T-girder section, and permits of the use of lighter material for the box so as to decrease the weight as much 90 as possible.

On this partition 10 may be arranged suitable means, as 12, for supporting saws, the said means being provided at their lower ends with hooks or the like 13 for this 95 purpose, as seen in Figures 1 and 4.

Depending from the top 1 are the strips 14, as seen clearly in Figures 3 and 4, between which and the central partition the upper edges of the saws are designed to be 100 retained. These saws are designed to be inserted and removed at the ends of the tool-box and for this purpose I provide at each end a door or closure 15, each of said closures being hinged, as at 16, to the end 105 of the top 1, as clearly shown in Figures 1, 3 and 5, it being, of course, understood that there is an opening at each end of the box which is closed by the doors 15 when the latter are in their vertical position, as seen 110 in Figures 1, 3 and 4.

In order to hold the doors or closures 15

in their open position, as seen in Figure 5, I provide the members 17, one for each door or closure, the same being made of sheet material flanged, as at 18, and secured by 5 suitable means, as screws or the like, to the under side of the closure 15, as will be readily understood upon reference to said Figure 5, the said member 17 comprising a main inclined portion and a member 19 ex- 10 tending at an angle therefrom and at right angles to the closure 15. By this means I obtain a strong brace and support which may be made of light material, yet suffi- 15 ciently strong to support the closure in its open position.

When the closure 15 is in the position seen in Figure 5, the brace and supporting member 17 has its lower end, which is preferably angled, as seen at 20, supported upon 20 the lug or the like 21, see Figure 5, which is formed on the plate 22 pivotally mounted on the edge of the partition 10, as seen at 23, the said plate 22 being formed with a right-angled portion 24 adapted to bear 25 against the side of the partition, as seen in Figures 5 and 6, and when the door is to be closed the said plate is turned upon its pivot into a reverse position, as indicated by dotted lines in Figure 5, when the right-angled portion 24 of said plate fits into a recess 25 in the end of the partition 10, as seen in Figure 5. The member 17 is then moved with the door so as to pass alongside the partition 10 and move along the side 35 thereof into the position indicated by dotted lines in Figure 5, to allow of closing of the door.

In order to protect the top 1 of the tool-box from injury or being marred during its 40 use as a trestle, I provide for the fastening of a strip of lumber or the like thereupon. This will be understood upon reference to Figure 5, in which 26 represents a strip of board or the like laid upon the top 1 and of sufficient length to extend over the two closures 15 when the latter are opened, and in order to fasten this strip against movement 45 relatively to the said top I provide a screw-threaded bolt 27 having a head or the like 50 28 by which it may be turned, the inner end being screw-threaded, as at 29, and preferably though not necessarily tapered to any great extent, the shank of this bolt passing loosely through an opening 30 in the closure 15 and through a metallic plate 31 secured to the under side of said closure. The bolt is provided adjacent its screw-threaded portion with a shoulder 32 of less diameter 55 than the opening 30 but of greater diameter 60 than the opening in the plate 31, as will be readily understood upon reference to Figure 5, so that, under ordinary conditions, when the member 15 is closed the bolt cannot come out and be displaced, yet it can 65 be readily screwed into the member 26 when

desired for such use. It will be understood that there is a similar bolt at each end of the box, that is one in each closure 15 for the same purpose.

The box may be provided at its lower 70 corners with suitable reinforcing stays or the like 33 in the form of corner brackets, as seen in Figure 1 and in detail in Figure 7.

In order to support the tool-box at a proper height to adapt it to serve as a trestle, 75 I provide at each corner of the box a leg 34, each leg being pivotally mounted by means of a suitable bolt or the like 35 passed through the leg near its upper end and through a plate 36 secured to said leg, the 80 bolt adapted to pass through an opening in the side portion of the box proper and engageable with a nut 37 which is relatively fixed upon the inner face of the portion 4, as seen best in Figure 8. In the construction shown this nut is rigid with a plate 38 which is secured to the inner face of the portion 4 by suitable means.

Each leg is designed to be held fixedly, either in its extended position, that shown 90 in Figures 1 and 4, or in a position at substantially right angles thereto alongside the portion 4, as indicated in Figure 2. This may be accomplished in various ways.

As seen in Figure 2, each plate 36 carries 95 two pins 39 and 40. These pins, or they may be integral with the plate, project through the leg 34, as seen in Figure 8, and are diametrically oppositely disposed and adapted to project into openings 41 and 42, 100 or 43 and 44, in the plates 33 and into the members 4 of the tool-box, as seen in Figure 8. When the leg is in extended or vertical position, as indicated by dotted lines in Figure 2, the pins 39 and 40 engage in the openings 43 and 44, but when it is desired to fold the leg against the side of the box, as shown by full lines in Figure 2, the bolt 35 is loosened and the leg pulled outward, as seen in dotted lines in Figure 8, and the leg 105 then turned on the bolt 35 as a pivot, the said bolt not being removed far enough to disengage it from the hole in the member 4 and then when the leg is in the proper horizontal position, lying against the member 4, 110 as seen in full lines in Figure 2, the bolt is again engaged with the nut 37 and the pins 39 and 40 will engage in the openings 41 and 42. The legs are thus held tightly 115 against the member.

Modifications in detail may be resorted to without departing from the spirit of the invention or sacrificing any of its advantages.

What is claimed as new is:—

1. A tool-box having a longitudinal partition, movably mounted closures, and means co-operable with said partition for holding said closures in open position.
2. A tool-box having a longitudinal partition, movably mounted closures, and means 130

carried by said closures and co-operable with said partition for holding said closures in open position.

3. A tool box having spreading sides and 5 legs secured thereto in the planes of spread, and a partition secured to the top of the box giving it a T-girder section so that the whole forms a substantial trestle.

4. A tool box having spreading sides and 10 legs secured thereto in the planes of spread, and a partition secured to the top of the box giving it a T-girder section so that the whole forms a substantial trestle, said box having an opening in the end, and a mova- 15 ably-mounted closure therefor adapted when moved to a horizontal position to form an extension of the top of the box.

5. A tool-box having a top member and end members, one of which end members 20 has an opening, a movably mounted closure for said opening, means for holding said closure in horizontal position in alinement with said top member, a longitudinal partition within said box having tool-holding means, 25 and means on said partition co-operating with said closure-holding means.

6. A tool-box comprising a top member, inclined sides, ends and bottom the top member forming the top of the box and the 30 trestle top and legs pivotally mounted adjacent the ends of the box and adapted to be held in extended position in inclined position in line with said inclined sides to form a trestle.

35 7. A tool-box comprising a top member, inclined sides, ends and bottom and legs pivotally mounted adjacent the ends of the box and adapted to be held in extended position in inclined position in line with said

inclined sides to form a trestle, and means 40 for holding said legs in folded position against the sides of the box.

8. A tool-box comprising a top member, inclined sides, ends and bottom and legs pivotally mounted adjacent the ends of the 45 box and adapted to be held in extended position in inclined position in line with said inclined sides to form a trestle, and means for holding said legs in folded position against the sides of the box, said means 50 serving to hold the legs in both their extended and folded positions.

9. A tool box having spreading sides and legs secured thereto in the planes of spread, a partition secured to the top of the box giv- 55 ing it a T-girder section so that the whole forms a substantial trestle, said box having an opening in the end, a movably-mounted closure therefor adapted when moved to a horizontal position to form an extension of 60 the top of the box, and a bracing means for said closure cooperable with the end of said partition.

10. A tool box having spreading sides and legs secured thereto in the planes of spread, 65 a partition secured to the top of the box giving it a T-girder section so that the whole forms a substantial trestle, said box having an opening in the end, a movably-mounted closure therefor adapted when moved to a 70 horizontal position to form an extension of the top of the box, a bracing means for said closure cooperable with the end of said partition, and means carried by said closure for securing a board thereto when the clo- 75 sure is in horizontal position.

In testimony whereof I affix my signature.
BENJAMIN N. BROUNER.
